UNITED STATES PATENT OFFICE

166,749

MAILBOX HOUSE

James I. Heinz, Arlington, Va.

Application July 10, 1950, Serial No. 11,031

Term of patent 7 years

(Cl. D74—9)

To all whom it may concern:

Be it known that I, James I. Heinz, a citizen of the United States, residing at Arlington, in the county of Arlington and State of Virginia, have invented a new, original, and ornamental Design for a Mailbox House, of which the following is a specification, reference being had to the accompanying drawing, forming a part thereof, wherein:

Fig. 1 is a front perspective view of a mailbox house, showing my new design; and

Fig. 2 is a perspective view of the disclosure in Fig. 1, but moved to an angle so as to disclose the rear of the mailbox house, the opposite side of Fig. 2 presenting substantially the same appearance as the side disclosed.

The broken line showings of the mailbox in Figs. 1 and 2 are for illustrative purposes only.

I claim:

The ornamental design for a mailbox house, as shown and described.

JAMES I. HEINZ.
